HOG RINGER

Clarence L. Austin, Morrison, Ill.

Application April 27, 1949, Serial No. 89,828

5 Claims. (Cl. 128—332)

1

This invention relates to an improved hog ringer and in particular it relates to a hog ringer having a magazine for the accommodation of a plurality of hog ring blanks.

The principal object of the invention is to provide an improved hog ringer having a magazine between the handles from which a series of hog ring blanks of the so-called Hill pattern may be fed into ring forming position.

Another object of the invention is to provide a hog ringer having improved crimping members which successively cam a ring blank forwardly and downwardly from the plane of the series of ring blanks into a snout-gripping position, and then form the ring.

A further object of the invention is to provide a hog ringer which may be adjusted to accommodate rings of several different sizes, rings of the Hill pattern normally being furnished in three sizes.

The invention is illustrated in a preferred embodiment in the accompanying drawings, in which—

Fig. 1 is a perspective view of the improved hog ringer in position to insert a ring in a hog's snout; Fig. 2 is a bottom plan view of the ringer with its jaws in open position; Fig. 3 is a side elevation similar to Fig. 2; Fig. 4 is a top plan view of the ringer with its jaws in closed position with a fully formed ring in the jaws; Fig. 5 is a bottom plan view similar to Fig. 4, with the magazine follower plate removed to better illustrate the construction of the ringer; Fig. 6 is a section taken as indicated at line 6—6 of Fig. 4; Fig. 7 is a fragmentary plan view of the inner surface of the magazine follower plate; Fig. 8 is a section taken as indicated on the line 8—8 of Fig. 3; Fig. 9 is a section similar to Fig. 8 with the crimping members in intermediate position and a ring therein in snout-gripping position; and Fig. 10 is a section taken as indicated on the line 10—10 of Fig. 6, showing a fully formed ring in the crimping members.

The hog ringer has a frame containing a magazine to receive a series of hog ring blanks, and a pair of cross-levers is pivotally mounted on the frame with its handles flanking the frame. A follower on the frame is urged forwardly by a spring, and engages ring blanks in the magazine to hold them forward against stop members carried on the jaws of the cross-levers. In rear of the stop members the cross-levers are provided with cooperating cam faces which first slide a ring blank downwardly and forwardly into snout-gripping position and then form the ring as the

handles of the cross-levers are moved together to close the jaws. A cross-head on the frame may have its forward travel adjustably limited and is linked to the cross-levers so as to adjustably limit the opening movement of the jaws, which may thus accommodate ring blanks of several sizes, and a spring urges said cross-head toward its forward position thus tending to keep the jaws in their adjusted open position.

Referring to the drawings in greater detail, a frame indicated generally at 11 is formed of a channel member so as to have a back 12, and side walls 13 and 14 which have their lower edge portions turned in, as seen in Figs. 8 to 10. As best seen in Figs. 5, 6 and 9, a guide member 15 is welded to the inside of the hollow, channel-like frame 11 at 15a, and extends to the open forward end thereof. The guide member 15 has a channel-like cross-section generally concentric with that of the frame 11 so as to provide a magazine for a series of ring blanks 16. The ring blanks are of the well known Hill pattern, and are preferably held together by a plastic or lacquer coating for easy loading of the magazine.

25 A pair of cross-levers 17 and 18 are pivotally mounted on the frame 11 by means of a rivet 19, the handles 20 and 21 of the cross-levers flank the frame and the jaws 22 and 23 thereof extend forwardly across the open end of the magazine. The jaws 22 and 23 are provided with flanges 24 and 25 which act as stop members for the ring blanks 16. Immediately to the rear of the stops 24 and 25 are crimping cams 26 and 27 (best seen in Figs. 8 and 9) which are positioned to flank the forward ring blank 16a of the series of ring blanks in the magazine. As best seen in Fig. 6 the jaws 22 and 23 and the crimping cams 26 and 27 slant forwardly and downwardly and, as shown in Fig. 8, the crimping cams have long outwardly flaring upper surfaces 26a and 27a, and short inwardly directed lower surfaces 26b and 27b. As the jaws close, the shoulders of the forward ring blank 16a are first gripped between the surfaces 26a and 27a which slide the ring blank downwardly and forwardly to a snout gripping position (see Fig. 9), at which point the ring blank shoulders are gripped by the lower surfaces 26b and 27b of the crimping cams, and as the closing of the jaws continues the blank 16a is closed to form a completed ring, as seen in Fig. 10.

Pivoted to the cross-levers 17 and 18 at 28 and 29, respectively, are a pair of links 30 and 31 which have their inner ends pivotally secured to a cross-head by means of a rivet 33 which extends through a guide slot 34 in the back 12 of

the frame 11. The rear portion of the guide slot 34 is broadened to form shoulders 35.

As best seen in Figs. 4 to 6, the cross-head 32 includes a main plate 36 which lies above the back 12 of the frame and is provided with a longitudinal slot 36a; and an adjustment plate 37 which lies beneath the back 12 and has a threaded abutment shoulder 38 projecting through the broad rear portion of the guide slot 34 to contact the main plate 36. A thumb screw 39 extends through the slot 36a and screws into the abutment shoulder 38 to hold the cross-head together. The bottom surface of the main plate and the top of the abutment shoulder are preferably laterally scored to provide good frictional engagement when the thumb screw 39 is tightened. It will be observed that the abutment shoulder 38 engages the shoulders 35 of the guide slot 34 to limit the forward travel of the cross-head, and that by moving the adjustment plate 37 with respect to the main plate 36 the extreme forward motion of the cross-head 32 may be adjusted. By reason of the links 30 and 31, this in turn adjustably limits the extreme opening of the jaws 22 and 23, so as to accommodate them to ring blanks of several sizes. A U-shaped spring receiver 40 at the rear of the main plate 36 has an arm extending beneath the back 12 of the frame 11, and a tension return spring 41 which extends from said arm to an aperture at the rear of the guide member 15 urges the cross-head 32 to its forward position and the jaws to their open position. Preferably, the adjustment plate 37 is provided with an indicator 42 which projects through the forward part of the guide slot 33 and may be aligned with suitable marks on the main plate 36 to indicate the proper adjusted position for ring blanks of any given size.

A magazine follower 43 has upright sides 44 and 45 and is of appropriate dimensions to slide in the slot formed by the side walls 13 and 14 of the main frame and the concentric side walls of the guide member 15. The upright sides 44 and 45 of the follower have their forward ends crimped at 46 and 47 to engage the series of ring blanks 16, and a tension spring 48 is stretched between a hook 49 at the rear of the follower 43 and an aperture in the guide member 15. Thus the spring 48 urges the follower 43 forwardly so as to feed the series of ring blanks 16 successively into position abutting against the stops 24 and 25 of the jaws, and between the crimping-cams 26 and 27. A stop lug 50 on the inner surface of the follower 43 engages with a lug 51 on the guide member 15 to limit forward motion of the follower; and to facilitate loading the magazine the rear edge portion of the guide member 15 is bent downwardly to form a lip 52 to engage the lug 50 and retain the follower in a retracted position. The follower makes a loose fit with the slot in which it rides so as to permit the lug 50 to be freed from the lip 52, thus allowing the follower to slide forward after the series of ring blanks 16 is fed into the magazine from between the jaws 22 and 23.

In loading the ringer, the thumb screw 39 is first loosened and the indicator 42 located in registry with the appropriate mark on the main plate 36 of the cross-head to adjust the extreme span of the jaws for the particular size of ring blank which is to be used. The thumb screw 39 may then be tightened to lock the cross-head in its adjusted position, and a series of ring blanks 16 may be fed into the magazine between the jaws 22 and 23. As pointed out above, this load-

ing operation is facilitated if the magazine follower 43 is first drawn rearwardly until the lug 50 engages the lip 52 to hold the follower in its retracted position. When the magazine is loaded with a series of ring blanks, the lug 50 may then be released from the lip 52 and the follower permitted to slide forward to engage the rear ring blank 16 in the series and hold the front ring blank 16a against the stops 24 and 25 of the jaws.

The animal to be ringed may be held in any convenient fashion and, as seen in Fig. 1, the ringer may be brought to the necessary position for inserting a ring into the hog's snout. It will be noted that the manipulation of the ringer is very easy because of the fact that the handles 20 and 21 of the cross-levers flank the frame 11, and thus are substantially perpendicular to the plane of a ring blank 16, so that the ringer may be brought toward the snout from the side. This is in contrast to the prior art hog ringers in which the handles are substantially parallel to the plane of a ring blank held in the jaws so that it is necessary to approach the hog's snout from above in order to have the ring blank in proper position for ringing. The manipulation of the improved ringer is far simpler for this reason, and it is easier for the operator to see that he is placing the ring properly in the cartilaginous portion of the snout.

As previously described, as the handles 20 and 21 of the cross-levers are compressed, the front ring blank 16a first is cammed downwardly and forwardly so that its ends project beyond the lower margins of the jaws and are clear of the succeeding ring blank. During the last portion of the closing motion the ring is formed by the crimping cams 26 and 27 and its tips close in a cartilaginous portion of the hog's snout.

When a ringing operation has been completed, the handles may be released, and the tension spring 41, acting through the cross-head 32, will return the cross levers 17 and 18 to their extreme open position. The spring-loaded magazine follower 43 then advances the next succeeding ring blank 16 between the crimping cams 26 and 27 and the ringer is ready for another ringing operation.

The foregoing detailed description is given for clearness of understanding only, and no unnecessary limitation should be understood therefrom, for some modifications will be obvious to those skilled in the art.

I claim:

1. A hog ringer, comprising: a hollow channel-like frame; a guide member mounted in said frame to provide a magazine for ring blanks; a spring loaded follower urging blanks in said magazine toward an open end thereof; and a pair of cross-levers pivotally mounted on the frame with their handles flanking said frame, each of said levers having a forwardly extending jaw provided with a stop for said ring blanks and a crimping cam in rear of said stop.

2. A hog ringer as specified in claim 1, wherein the magazine is arranged to receive ring blanks of several different sizes, and means are provided for adjustably limiting the separating movement of the jaws to accommodate the jaws to rings of several different sizes.

3. A hog ringer as specified in claim 1, wherein the crimping cam on each jaw is so shaped as to successively move the end ring blank in the magazine out of the plane of the remaining ring blanks and into snout gripping position.

4. A hog ringer as specified in claim 1, wherein the cross-levers are linked to a cross-head carried on the frame, and means are provided for adjustably limiting the forward travel of the cross-head to control the maximum separation of the jaws whereby the ringer may accommodate ring blanks of different sizes.

5. A hog ringer, comprising: a hollow channel-like frame; a guide member mounted in said frame to provide a magazine for a series of ring blanks; a spring loaded follower urging said blanks toward an open end of said magazine; a pair of cross-levers pivotally mounted on the frame with its handles flanking the frame and the magazine, each of said levers having a forwardly extending jaw provided with an inwardly facing ring stop against which ring blanks in the

magazine are thrust by said follower, and having a crimping cam in rear of said stop shaped to move the end ring blank in the magazine downwardly and forwardly into snout gripping position and then form a ring; a cross-head traveling in a slot in said frame; a movable abutment member on said cross-head cooperating with a shoulder on said slot to adjustably limit the forward travel of the cross-head; spring means urging said cross-head toward its forward position; and links between the cross-head and the handles of the cross-levers whereby the cross-levers are urged to open position by said spring means.

CLARENCE L. AUSTIN.
